DESIGN FOR A MECHANICAL LEAD PENCIL

Robert Back, Chicago, Ill., assignor to The Wahl
Company, Chicago, Ill., a corporation of Dela-
ware

Application December 30, 1935, Serial No. 60,342

Term of patent 7 years

To all whom it may concern:

Be it known that I, Robert Back, a citizen of the United States, residing at Chicago, in the county of Cook and State of Illinois, have invented a new, original, and ornamental Design for a Mechanical Lead Pencil, of which the following is a specification, reference being had to the accompanying drawing, wherein

Fig. 1 is a side view of a mechanical lead pencil embodying my new design;

Fig. 2 is another side view of same at approximately 45° from that shown in Fig. 1; and

Fig. 3 is an end view at the lower end of Fig. 1.

I claim:

The ornamental design for a mechanical lead pencil, substantially as shown.

ROBERT BACK.
